UNITED STATES PATENT OFFICE

100,696

DESIGN FOR A HYDRAULIC FEED CONTROL PANEL

Kenneth R. Herman, Detroit, Mich., assignor to
Vickers, Incorporated, Detroit, Mich., a corpo-
ration of Michigan

Application May 25, 1936, Serial No. 62,822

Term of patent 14 years

To all whom it may concern:

Be it known that I, Kenneth R. Herman, a citizen of the United States of America and residing at Detroit, in the county of Wayne and State of Michigan, have invented a new, original, and ornamental Design for a Hydraulic Feed Control Panel, of which the following is a specification, reference being made to the accompanying drawing, forming part thereof.

The drawing is a perspective view of a hydraulic feed control panel showing my new design.

I claim:

The ornamental design for a hydraulic feed control panel substantially as shown.

KENNETH R. HERMAN.
